UNITED STATES PATENT OFFICE.

EDGAR M. SORENG, OF MILWAUKEE, WISCONSIN, ASSIGNOR TO BRIGGS & STRATTON COMPANY, OF MILWAUKEE, WISCONSIN, A CORPORATION OF WISCONSIN.

HEADLIGHT REGULATOR.

1,411,754.

Specification of Letters Patent. Patented Apr. 4, 1922.

Application filed November 24, 1916. Serial No. 138,119.

To all whom it may concern:

Be it known that I, EDGAR M. SORENG, a citizen of the United States, and resident of Milwaukee, in the county of Milwaukee and 5 State of Wisconsin, have invented new and useful Improvements in Headlight Regulators, of which the following is a description, reference being had to the accompanying drawings, which are a part of this specification.

This invention relates to headlight regulators for automobile headlights of the type in which a magneto or other alternating current generator is relied upon as the source of 15 current supply for the electric headlights.

The object of the present invention is to provide means whereby the failure of one of the lights of such a system will not cause the other to receive an excessive current liable to injure it but which will automatically introduce a choking effect upon the circuit of the remaining lamp and keep normal the current flow therethrough when the one headlight burns out or is otherwise out of 25 circuit.

With this object in view the invention consists of the headlight regulator as herein claimed and all equivalents.

Referring to the accompanying drawings 30 in which like characters of reference indicate the same parts in the different views:

Fig. 1 is a longitudinal sectional view of a headlight regulator constructed in accordance with this invention;

Fig. 2 is a front view thereof; and, 35 Fig. 3 is a diagram of circuit connections of such headlight regulator.

In these drawings 10 indicates a box-like iron casting forming a casing adapted to 40 be secured to a suitable part of the automobile. In this cup-shaped casing is placed a magnet spool 11 composed of a pair of magnet windings surrounding the same core 12, which as shown may preferably 45 consist of an ordinary bolt. The magnet coil is held in place within the casing by an insulating composition 13 which is poured or otherwise placed in the casing around the magnet in a liquid or plastic condition and on hardening firmly holds the 50 parts together and forms a solid filling for the casing. Leads of the windings are previously passed out through openings in the casing, there being three of them as shown,

one lead wire 14 being common to both windings and the other lead wires 15 and 16 respectively extending from the other ends of the windings. 55

From their common terminal or lead wire 14 the two windings 17 and 18 of the magnet coil 11 turn in opposite directions so that they are opposed to each other, the object being that they should normally neutralize each other with the same current flow through both headlights to which the lead 60 wires 15 and 16 are connected. 65

In installing the regulator the grounded magneto 19 is connected through a switch 20 with the common lead wire 14 and the lead wires 15 and 16 are respectively connected 70 with headlights 21 and 22 which are grounded. With the switch closed the alternating current from a generator 19 is divided, each branch passing through one of the windings of the magnet coil 11 and then through one 75 of the headlights. With the two headlights connected in multiple and their branch circuits including the oppositely wound coils of the magnet which neutralize each other in their magnetic effect no impedance is 80 offered to the flow of current other than the resistance of the winding, for the tendency of one coil to produce magnetism in one direction is equal to the tendency of the other to produce magnetism in the opposite direction. When, however, one branch circuit becomes broken, as by the burning out of one 85 of the headlights, the tendency of the magnet winding connected with the other headlight to produce magnetism is unresisted and the self-inductance of the magnet acts to impede the current flow therethrough and so choke the flow of current to the remaining headlight as to compensate for the absence 90 of the draft of current by the other headlight and so maintain conditions practically 95 normal for such remaining headlight.

The number of ampere turns in the magnet windings is adjusted so that at maximum speeds there will not be an excessive current 100 through the lamps and the resistance of the windings is adjusted so that when both lamps are in operation there will not be an excessive current through them.

The iron casing, besides serving as a housing to protect the coil and as a means for securing it in place, forms a return conductor to complete the magnetic circuit through 105

the core, the ends of the core being sufficiently close to the walls of the casing for this purpose.

The regulator is simple and inexpensive in its construction and having no movable parts is durable and requires no attention. It is efficient for the purpose intended, enabling the use of one headlight if desired or when necessary through accident or the burning 10 out of a lamp.

What I claim as new and desire to secure by Letters Patent is:

1. A headlight regulator for automobiles and the like using alternating current supply, comprising a cup-shaped iron casing, a cementitious material filling the casing, and a magnet spool embedded in the cementitious material with the ends of its metallic core close to the wall of the casing so as to utilize 15 the casing as a return path for the magnetic 20 flux.

2. A headlight regulator for automobiles and the like using alternating current supply, comprising a cup-shaped iron casing, 25 having openings in the bottom thereof, a magnet spool contained therein with the ends of its metallic core close to the walls of the casing to utilize the casing as a return path for the magnetic flux, said magnet spool 30 having its lead wires pass out of the casing through said openings, and a filling of cementitious material in the cavity of the cas-

ing surrounding the magnet spool and the lead wires.

3. As an article of manufacture a headlight regulator for automobiles and the like 35 using alternating current supply, comprising a magnet spool, an iron bolt passing through the magnet spool and serving as a core therefor, a cup-shaped iron casing with the cavity 40 at its back containing the magnet spool with the ends of the bolt close to the walls thereof whereby the casing constitutes a return path for the magnetic flux, there being openings 45 in the front of the casing through which the lead wires of the magnet windings pass, and a hardened filling in the cavity of the casing surrounding the magnet spool and its lead wires.

4. As an article of manufacture, a magnet 50 spool, a metal core therefor, a metal casing having a cavity, and a hardened filling in the cavity of the casing having the magnet spool embedded therein with the ends of the 55 core close to the walls of the casing whereby the casing constitutes a return path for the magnetic flux thereof.

In testimony whereof, I affix my signature, in presence of two witnesses.

EDGAR M. SORENG
